THERMAL RELIEF VALVE

Ernest A. Lowe, Fanwood, N. J., assignor to The
Airelease Corporation, Jersey City, N. J., a cor-
poration of Delaware

Application May 7, 1938, Serial No. 206,548

11 Claims. (Cl. 169—17)

This invention relates to automatic fire extinguishing systems designed to automatically discharge a fire extinguishing fluid, such as water, to a fire for extinguishing purposes. In its application, it is preferred to apply the invention to what is known in the art as a "dry-pipe" system, to wit: one in which the liquid distributing system preferably comprises a riser pipe connected to a source of fluid supply and branch or distributing pipes which are connected with the riser. The riser and distributing pipes are either empty or filled with compressed air which normally is retained within the system by means of closed fusible sprinkler heads mounted at intervals on the branch or distributing pipes. The discharge of the extinguishing medium from the sprinkler heads usually only is permitted when one or more of them fuses by the action of heat generated by a fire in order to open the head and to permit the extinguishing fluid to flow thereto for discharge therefrom.

As is well known, one of the objections to a dry-pipe system, especially one in which the riser and distributing pipes are normally filled with compressed air, is the delay, which ordinarily must ensue, in having the extinguishing fluid available at the sprinkler head for immediate discharge therefrom. In a typical dry-pipe system, before the extinguishing fluid is available for discharge, a sprinkler head must first fuse and open and air must then be forced from the pipes intervening between the inlet valve and the open sprinkler head. This delay ordinarily makes it possible for the fire to progress to an extent sufficient to cause considerable fire damage before the system is brought into operation.

The principal object of the invention, with the above explanation in view, is the production of a thermal relief valve of improved construction adapted to operate on a sudden rate-of-rise of temperature such as would be produced on the occurrence of a fire so that, by its action, it is adapted to "condition" the system with the extinguishing fluid, that is, it permits the system to be relieved of air pressure and to be filled with the extinguishing fluid which flows to, or in proximity to, the sprinkler head or heads whereby it is accessible for instant discharge therefrom upon the fusing of and consequent opening of said sprinkler head or heads. The invention therefore permits the conversion of what is ordinarily a dry-pipe system into a wet-pipe system with its many attendant advantages.

A further object of the invention is the provision of a thermal relief valve of simple con-

struction which shall be adapted, and in furtherance of the above objects, to be readily applied to any conventional form of dry-pipe extinguishing system now in use and at small expense and without any general reorganization or modification of the system per se.

The invention is an improvement on the invention of my prior application for patent for Thermal relief valve, filed June 12, 1936, Ser. No. 84,816 in which the advantages of a device of this general character are set forth in great detail and many of which do not require repetition or amplification in this specification, further objects and advantages of the invention of the improved device being apparent from the subjoined description taken in connection with the accompanying drawing in which:

Fig. 1 is a side elevation of a fragmentary portion of a conventional form of dry-pipe fire extinguishing system showing the present invention as used in conjunction therewith.

Fig. 2 is a vertical central section taken through the thermal relief valve; and

Fig. 3 is a horizontal section taken on the line 3—3 of Fig. 2.

Referring in detail to the several figures of the drawing:

The riser pipe of a conventional dry-pipe fire extinguishing system is indicated at 10 and it is provided with one or more branch or distributing pipes connected at intervals therewith which are mounted preferably adjacent the ceiling 12 of a room or other enclosure. These branch or distributing pipes 11 are supplied at spaced intervals thereon with normally closed sprinkler heads 13 having fusible links adapted to fuse to automatically open the heads when heat of a sufficient degree has been attained as, for instance, by that caused by a fire. The system is ordinarily filled with air under pressure which must be permitted to escape upon the occurrence of a fire to be replaced by the fire extinguishing medium, such as water, which normally is excluded from the system by an automatic main dry valve shown diagrammatically at 15 and which may be of any suitable type and construction. The main dry valve is normally held closed by the pressure of the compressed air in the system exerted thereagainst to prevent the passage of the extinguishing fluid from a source of supply to the distributing system.

In some cases it is desirable to employ an exhauster or accelerator 16 also shown diagrammatically and employed for detecting the decrease in air pressure in the system occasioned

by fire conditions and also to hasten the discharge of air from the system. Any form of alarm or other signal, such as the bell indicated at 17, may be employed in association with the 5 dry valve 15 to give a signal when the system is becoming filled with water or other fire extinguishing fluid. A suitable gate valve operable by hand is indicated at 18, its function being to control the flow of water or other extinguishing 10 medium from a water or fluid main 19 or other source of supply.

As is usual in this type of apparatus, the dry valve 15 requires an appreciable lowering of the air pressure in the system before it will operate 15 and accordingly it is necessary for one of the sprinkler heads 13 to fuse and open to permit the escape of compressed air from the system and allow the automatic opening of said dry valve 15 by the release of pressure thereagainst. 20 By use of the present invention the dry valve is permitted to open in advance of the fusing of a sprinkler head and to thereby obviate the various objections inherent in the old type of apparatus. This automatic opening of the dry valve and the 25 escape of the compressed air from the system permits of the replacement of the air by water or other extinguishing fluid in the system so that when a sprinkler head finally opens from the heat generated by a fire, the extinguishing medium 30 will be immediately available at the sprinkler head to be instantly discharged therefrom. The sprinkler heads 13, as illustrated, extend upwardly toward the ceiling and a T-connection 20 is preferably interposed therebetween 35 and the distributing or branch pipes 11. The thermal relief valves are then screwed or otherwise secured to suitable pipe connections 21 connected to the T-connection 20 whereby said relief valves are positioned adjacent the ceiling 40 and in communication with the piping of the fire extinguishing system.

Referring in detail to Figures 2 and 3, 22 indicates an annular fluid chamber having a base 23 screwed therein and an upper wall 24 also 45 screwed therein as illustrated. The base 23 is provided with a downwardly depending pipe receiving member or extension 24' detachably receiving the screw-threaded end of pipe connection 21. Said base 23 is also provided with an 50 upwardly extended inlet or stand pipe 25 extending within the chamber 22 and having a drain opening 26 therein. An annular flange or rib 26' preferably forms an integral part of said base and receives a spherical and movable valve 55 closure member 27 of buoyant material so that it will float in a liquid. The rib or flange 26' provides between the wall of chamber 22 and stand pipe 25 a ball-race for the spherical valve member 27. Said rib is also provided with a plurality of openings 26A extending therethrough and through sediment and water may be drained 60 to and through the drain opening 26.

The upper wall 24 of the fluid chamber is specially recessed to form a valve-receiving 65 pocket as at 28 preferably of the specific configuration shown and provided with an upper flattened wall and an annular wall merging therewith whose diameter is of a size permitting it to snugly receive the spherical valve member 70 27. An opening 29 communicates with said recess 28 and is normally closed at its outlet side by a removable cap 30 and may be closed at its inlet side by the spherical valve member 27. The inlet pipe 25 is provided with an L-shaped 75 deflector pin 31, one leg of which is fastened to

the wall of the pipe 25 and which pin acts to prevent the spherical valve 27 from resting or becoming seated on the top of the pipe 25 whereby the possibility of the obstruction of the free passage between the pipe 21 and the fluid chamber 22 is obviated. 5

The upper wall 24 constitutes the base of an automatic sprinkler head mechanism, the construction of which is more fully described in my co-pending application for patent for Sprinkler head filed of even date herewith. Said sprinkler head portion is provided with an air chamber 25' having a lower wall or base 26'' provided with an opening 27' therein and centrally thereof and a dome-shaped wall 28', the lower flanged 15 edge of which is secured to the base 26'' by a corresponding flange on the edge of said base. A flexible diaphragm 29' is positioned beneath said base 26'' and its annular edge is fastened intermediate said base and the annular flange 30' of 20 a supporting member 31' provided with an opening 32 preferably in vertical alignment with the opening 27' in the base 26''. The chamber 25' is connected to the upper wall 24 by upwardly and outwardly flaring arms or supports 33 and 25 the interior mechanism is preferably protected from dust and exposure by an annular cover 34 which is removably mounted in position by frictional engagement of the lower peripheral flanged edge thereof with said upper wall 24. 30

A spring metallic strip constituting a co-operating detent member is indicated at 35. One end thereof is secured to the supporting member 31' and said strip carries a pin 32' engaging the underside of the diaphragm 29' or in position 35 to be engaged thereby. A stop 33' is also carried by said strip to engage the supporting member 31' and limit the movement of the strip toward the diaphragm 29'.

A strut support is indicated at 34' and is 40 positioned centrally of the structure and is preferably fastened thereto by arms 35' secured to the upper wall 24. Said strut support is provided with a central screw-threaded opening receiving a screw-threaded nut or plug 36 as shown. 45 A detent roller is indicated at 31. Its ends are journaled in bearings 38 which may be fastened to the underside of supporting member 31' and it is provided with a flattened portion or a flat side or recessed portion 39 and with a detent 50 lug 40 normally engaged by the edge of the free end of the spring co-operating member 35. It is also provided with a stop 40' for engagement with member 31' to limit the degree of rotation thereof. 55

The strut mechanism comprises a main strut member 41 normally engaging the top of the cap 30 to hold it on its seat. The upper end of said strut engages the angled portion of a second strut member 42 and the upper end of strut member 42 engages the plug or nut 36 while its lower end engages within an offset portion of a vertically extending strut 43 whose lower end engages a lug 44 while its upper end engages the high or rounded portion of the roller detent 65 31. When the strut mechanism is "set" and in operative position, as shown in Fig. 2, the members thereof are collapsibly held in this position by the tightening of the nut or plug 36 within the strut support 34. 70

Should a fire occur resulting in a sudden rate-of-rise of temperature, the air in chamber 25' heats and expands very rapidly and such expanded air flows through the opening 27' and exerts downward pressure against the diaphragm 75

29. This acts to press the pin 32' downwardly against the spring strip 31' and thereby release the free end of said spring strip from its engagement with the detent lug 40 on roller detent 31 5 and thus permit a spring 45 which is fastened to said detent roller and to any fixed portion of the structure, such as one of the arms 33, to be brought into action to partially rotate the roller in its bearings and release the upper end 10 of strut member 43 from its engagement with the high or rounded portion of the detent roller and permit said upper end to pass or slide through the recessed portions 39 of said roller.

The above action leaves the strut member 43 15 unsupported at its upper end and in consequence the entire strut mechanism comprising strut members 41, 42 and 43 collapses and the cap 30 thereupon is automatically removed from its seat by the pressure of the compressed air in 20 chamber 22 and in the system which then discharges through the opening 29 to the outside atmosphere.

It is preferred to provide the lower wall 26' of chamber 25' with a breather 46 having an orifice or opening 47 extending vertically therethrough which communicates with said chamber and with the outside atmosphere and which acts to equalize the air pressure on the upper and lower faces of the diaphragm 29'. This breather 30 compensates for any normal rise in temperature, due to weather or other conditions, which would result in a gradual increase of air pressure in the chamber 25' permitting it to escape through the orifice 47. This orifice, however, is 35 insufficient in size to accommodate the release of any abnormal expansion of air in chamber 25' due to a sudden rate-of-rise in temperature, as from a fire, and such expanded air must therefore necessarily flow through opening 27' and exert pressure against diaphragm 29' to flex the same and actuate the sprinkler head mechanism in the manner described. The actuation of said mechanism is very rapid because of the rapidity with which the detent spring-controlled roller 31 40 functions when released.

After release of the cap 30 from its seat following the actuation of the sprinkler head mechanism, the compressed air in the fire extinguishing system rushes from the fluid chamber 22 and through the opening 29 thus permitting the main valve 15 to automatically open as it then is released from air pressure. This allows the extinguishing fluid, such as water, to flow into the system and condition it preparatory to the fusing 50 of one or more of the sprinkler heads 13 for discharge of the fluid therefrom. After the compressed air has been discharged, water flows into the fluid chamber 22 to float the spherical valve member 27 and raise it upwardly with the water 55 until it becomes seated in the pocket or depression 28 to close the opening 29 and thereby prevent any unnecessary expulsion or discharge of water from the apparatus which would result in water damage to property. After the apparatus 60 has functioned and is in condition for re-setting, water remaining in chamber 22 is drained therefrom through drain opening 26 and the spherical valve 27 again assumes the position shown in Fig. 2 and is prevented from having become seated 65 on the end of pipe 25 by means of the deflector pin 31 as has heretofore been explained.

When the device functions from the action of heat and the compressed air rushes from the system into chamber 22 and out of opening 29, 70 a sufficient portion thereof strikes against the

upper wall of the depression 28 and by reason of the configuration of said depression, is deflected thereby downwardly against the top or upper portion of spherical valve 27. This action prevents said spherical valve from being carried 5 upwardly in said chamber with the compressed air and thus obviates any possibility of said spherical valve closing the opening 29 prior to the inrush of water into chamber 22. It has been found in practice that the action of the compressed air 10 thus deflected against the top of the spherical valve holds it down against the uprush of air escaping from chamber 22 and in addition has the effect of causing said valve to travel rapidly in a circular direction and in a horizontal plane 15 on ball-race 26 until the discharge of compressed air into chamber 22 has terminated having the said valve ready to float in and with the rise of water in said chamber.

As an additional means of sounding an alarm 20 I have provided the shield or casing 34 with a conventional form of whistle 48 mounted in any manner in the wall of said casing and operable by means of the compressed air discharged into the device and which finds an outlet through 25 said whistle. I also prefer to seal the outer surface of said whistle with a paper or other frangible seal 49 which is preferably colored with a color contrasting to that of the cover 34, which seal is broken by the outrush of compressed air 30 through the whistle 48. The purpose of the seal is to permit an inspector to be apprised as to which, if any, of the thermal relief valves has 35 functioned, by mere visual inspection of the seals described to ascertain which ones have been broken and without the necessity of removing the shield for inspection of the interior mechanism. In some cases also I prefer to serrate the upper edge of casing 34 form it with openings 50 to provide for the escape of compressed air should 40 an excessive amount thereof be present.

The invention claimed is:

1. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow to the system prior to the attainment of a temperature sufficient to actuate the sprinkler head to permit it to open and discharge the extinguishing medium therefrom, said means including a walled fluid chamber having an inlet connected with the source of extinguishing fluid supply and having a valve-receiving pocket in a wall thereof and an outlet opening communicating with said pocket, a closure cap closing said outlet opening and normally subjected to the air pressure in the system, restraining means for holding the cap in a closed position, means for rendering said restraining means inoperative to permit of the automatic removal of said cap by said air pressure and a spherical buoyant valve adapted to be received by said pocket to close said outlet opening upon the admission of the extinguishing fluid to said fluid chamber.

2. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow to the system prior to the attainment of a temperature suffi- 70 75

cient to actuate the sprinkler head to permit it to open and discharge the extinguishing medium therefrom, a walled fluid chamber having a valve-receiving pocket in a wall thereof and an outlet opening communicating with said pocket, said means including a stand-pipe supported in the fluid chamber in alignment with said pocket and connected to the source of extinguishing fluid, means closing said outlet opening and normally subjected to the air pressure in the system, restraining means for holding the closing means in closed position, means for rendering said restraining means inoperative to permit of the automatic opening of said closing means by said air pressure, and a spherical buoyant valve adapted to be received by said pocket for closing said outlet opening upon the admission of the extinguishing fluid to said fluid chamber.

3. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow to the system prior to the attainment of a temperature sufficient to actuate the sprinkler head to permit it to open and discharge the extinguishing medium therefrom, said means including a fluid chamber comprising an annular wall and a base and upper wall secured thereto, said upper wall being provided with a valve-receiving pocket and an outlet opening communicating therewith, means normally closing said outlet opening and normally subjected to the air pressure in the system, restraining means for holding the closing means in closed position, means for rendering said restraining means inoperative to permit of the automatic opening of said closing means by said air pressure, a stand-pipe supported in the base of said chamber in alignment with said valve-receiving pocket, an annular rib on said base providing a ball-race with the wall of said stand-pipe and a spherical buoyant valve normally engaging said ball-race and adapted for reception by said pocket for closing said outlet opening.

4. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow to the system prior to the attainment of a temperature sufficient to actuate the sprinkler head to permit it to open and discharge the extinguishing medium therefrom, said means including an annular fluid chamber provided with a valve-receiving pocket and an outlet opening communicating therewith, a closure for said outlet opening and normally subjected to the air pressure in the system, restraining means for holding the closure in closed position, means for rendering said restraining means inoperative to permit of the automatic opening of said closure by said air pressure, a stand-pipe mounted in said chamber in alignment with said pocket and provided with a drain opening therein, a spherical buoyant valve in said chamber for reception by said pocket to close said outlet opening and means carried by said stand-pipe to prevent said spherical valve from becoming seated thereon.

5. A dry-pipe sprinkler system wherein a fire extinguishing fluid is normally excluded until a

fire occurs and wherein the system is filled with air under pressure, comprising in combination with a fusible sprinkler head, of means adapted to release the air from the system and to permit the fire-extinguishing fluid to flow to the system prior to the attainment of a temperature sufficient to actuate the sprinkler head to permit it to open and discharge the extinguishing medium therefrom, said means including a thermal device responsive to an abnormal rate-of-rise of temperature and comprising an air chamber, a flexible diaphragm in association therewith, a support having an opening therein for communication with the source of extinguishing fluid supply, a closure normally closing said opening, means connecting said air chamber and said support, mechanism connecting said diaphragm and said closure for normally retaining said closure in closed position, a spring-actuated detent for operating said mechanism to release said closure upon movement of said diaphragm, a removable shield covering said mechanism, a whistle carried by said shield for actuation by the compressed air in the system after the removal of said cap and a valve for automatically closing said opening by the flow of the fire extinguishing fluid into the system.

6. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow to the system prior to the attainment of a temperature sufficient to actuate the sprinkler head to permit it to open and discharge the extinguishing medium therefrom, said means including a thermal device responsive to an abnormal rate-of-rise of temperature and comprising an air chamber, a flexible diaphragm in association therewith, a support having a valve-receiving pocket therein and an opening communicating with said pocket, a closure normally closing said opening, mechanism connecting said diaphragm and said closure for normally retaining said closure in closed position, a spring-actuated detent for operating said mechanism to release said closure upon movement of said diaphragm, a fluid chamber communicating with the source of extinguishing fluid and with said valve-receiving pocket and opening and a spherical buoyant valve member within said chamber adapted to be received by said pocket for closing said opening.

7. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow to the system prior to the attainment of a temperature sufficient to actuate the sprinkler head to permit it to open and discharge the extinguishing medium therefrom, said means including a fluid chamber comprising an annular wall and a base and upper wall secured thereto, said upper wall being provided with a valve-receiving pocket and an outlet opening communicating therewith, means closing said outlet opening and normally subjected to the air pressure in the system, restraining means for holding the closing means in closed position, means for rendering said restraining means inoperative to permit of the automatic opening of said closing means by said air pres-

sure, a stand-pipe supported in the base of said chamber and provided with a drain opening communicating with the system and an annular rib on said base provided with an opening communicating with said drain opening and a buoyant valve normally engaging said rib and adapted to be received by said pocket for closing said outlet opening.

8. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow to the system prior to the attainment of a temperature sufficient to actuate the sprinkler head to permit it to open and discharge the extinguishing medium therefrom, said means including a thermal device responsive to an abnormal rate-of-rise of temperature and comprising an air chamber, a flexible diaphragm in association therewith, a support having an opening therein for communication with the source of extinguishing fluid supply, a closure normally closing said opening, means connecting said air chamber and said support, mechanism connecting said diaphragm and said closure for normally retaining said closure in closed position, a spring-actuated detent for operating said mechanism to release said closure upon movement of said diaphragm, a removable shield covering said mechanism, an audible signal visibly mounted in a wall of said shield for actuation by the pressure of the compressed air in the system after the removal of the cap and a buoyant valve for automatically closing said opening upon the flow of the fire extinguishing fluid into the system.

9. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow thereto prior to the attainment of a temperature sufficient to open the sprinkler head, said means including a walled fluid chamber having an inlet connected with the source of extinguishing fluid supply and having a valve-receiving pocket formed in a wall thereof in vertical alignment with said inlet and having a flattened upper wall forming a part of said fluid chamber and an outlet opening communicating with said pocket, means for closing said outlet opening and normally subjected to the air pressure in the system, restraining means for holding said closing means in closed position, means for rendering said restraining means inoperative to permit of the automatic opening of said closing means by said air pressure, and a spherical buoyant valve adapted to be retained in inoperative position in said chamber by the force of the compressed air deflected downwardly by the flattened wall of said pocket against said valve and adapted to be carried by the extinguishing fluid to operative position within said pocket to close said outlet opening upon a cessation of the discharge of compressed air through said inlet and the consequent flow of the extinguishing medium within said chamber.

10. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow thereto prior to the attainment of a temperature sufficient to open the sprinkler head, said means including a fluid chamber comprising an annular wall and an upper wall and a lower wall connected thereto, said upper wall being provided with a pocket therein having an upper flattened wall and an annular wall merging therewith and having an outlet opening communicating therewith, means closing said outlet opening and normally subjected to the air pressure in the system, restraining means for holding said closing means in closed position, means for rendering said restraining means inoperative to permit of the automatic opening of said closing means by said air pressure, an inlet pipe connected with the system and mounted in the lower wall of the chamber and extending within the chamber in alignment with the upper flattened wall of said pocket and a spherical buoyant valve normally lying in inoperative position in engagement with the lower wall of the chamber and intermediate its annular wall and said inlet pipe and adapted to be retained in such inoperative position by the force of the compressed air discharged from said inlet pipe and deflected downwardly by the upper flattened wall of said pocket and against said spherical valve and adapted to be carried by the extinguishing fluid to operative position within said pocket to close said outlet opening upon cessation of the discharge of compressed air through said inlet pipe and the consequent flow of the extinguishing medium within said chamber.

11. A dry-pipe sprinkler system wherein a fire extinguishing fluid is normally excluded until a fire occurs and wherein the system is filled with air under pressure, comprising in combination with a fusible sprinkler head, of means adapted to release the air from the system and to permit the fire-extinguishing fluid to flow thereto prior to the attainment of a temperature sufficient to open the sprinkler head, said means including a chamber having an inlet connected to the source of extinguishing fluid supply and also having an outlet, means closing said outlet and normally subjected to the air pressure in the system, restraining means for holding said closing means in closed position, means for rendering said restraining means inoperative to permit of the automatic opening of said closing means by said air pressure, deflecting means associated with said chamber, and a buoyant element normally lying in inoperative position in said chamber and adapted to be retained in such inoperative position by the force of the compressed air discharged from said inlet against said deflecting means and deflected thereby against said element, said element being adapted to be carried by the extinguishing fluid to operative position to close said outlet upon cessation of the discharge of compressed air through said inlet and the consequent flow of extinguishing fluid therethrough and to said chamber.

ERNEST A. LOWE.
